US0D1051660S

(12) **United States Design Patent** (10) **Patent No.:** **US D1,051,660 S**
(45) **Date of Patent:** **** Nov. 19, 2024**

(54) **LID**

(71) Applicant: **Qian Dong**, Xuzhou (CN)

(72) Inventor: **Qian Dong**, Xuzhou (CN)

(**) Term: **15 Years**

(21) Appl. No.: **29/953,083**

(22) Filed: **Jul. 19, 2024**

(51) LOC (14) Cl. **07-02**

(52) U.S. Cl.

USPC **D7/392**

(58) **Field of Classification Search**

(57) **CLAIM**

The ornamental design for a lid, as shown and described.

DESCRIPTION

FIG. 1 is a front, left, top perspective view of a lid, showing my new design;

FIG. 2 is a rear, right, bottom perspective view thereof;

FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the reduced scale thereof;

FIG. 8 is a bottom plan view of the reduced scale thereof; and,

FIG. 9 is a front, left, top perspective view of its enlarged scale in an alternate configuration.

The dashed broken lines in the figures are for the purposes of illustrating portions of the lid and form no part of the claimed design.

1 Claim, 9 Drawing Sheets
